UNITED STATES PATENT OFFICE.

HENRY E. BIGGINS, OF WALLINGFORD, CONNECTICUT, ASSIGNOR TO THE BIGGINS-RODGERS COMPANY, OF SAME PLACE.

DESIGN FOR A MIRROR PLATEAU.

SPECIFICATION forming part of Design No. 24,739, dated October 8, 1895.

Application filed June 24, 1895. Serial No. 553,920. Term of patent 7 years.

To all whom it may concern:

Be it known that I, HENRY E. BIGGINS, a citizen of the United States, residing at Wallingford, in the county of New Haven and State of Connecticut, have invented a certain new and useful Design for Mirror Plateaus, of which the following is a specification.

Referring to the accompanying drawings, which illustrate the invention, Figure 1 is a perspective view of a plateau, showing the design from one side. Fig. 2 shows a side elevation of the lower part or base of the plateau in order to show the design of the base from a different point of view from that of Fig. 1.

The leading feature of my design consists in a rococo band or base and feet with plain fields above the feet and surmounted by a plain rim with an ornamental picket or open filigree border that inclines toward the center of the mirror-top of the plateau.

The band or base 1 above the curved feet 2 shows a Louis XV polished shield or plain field 3, with a rounded surface that is somewhat larger at the top than at the bottom and that is outlined by a rococo border 4. The band or base around the rococo border of the shield is solid metal, and the surface of this solid portion is stippled or indented, as shown at 5. Surrounding this solid portion and out-

coco curves 6, and from these border-scrolls the florid rococo scrolls 7, with openings between them, branch off in each direction until they join the scrolls that branch from the adjacent shields above the next feet, of which there are four or more. The band or base curves outward somewhat from the top, then downward to the feet, which curve outward still farther, as shown in Fig. 1, and the open or perforated part of the band or base is designed so that it is not as deep at the middle portion between the feet as it is where the rococo scrolls branch off from the solid portion adjacent to the shields that are above the feet. Above the rococo band or base 1, which is band-like in outline, is a narrow band or rim 8, along the upper edge of which is an ornamental border of filigree or open picket work, as the border of ivy leaves 9, that is shown in Fig. 1. This ornamental border on the upper edge of the rim inclines inward over a portion of the edge of the mirror-top of the plateau.

I claim as my invention—

The rococo design for a mirror plateau herein shown and described.

HENRY E. BIGGINS.
